Attorneys.

UNITED STATES PATENT OFFICE.

JOSEPH V. RAY, OF GREENSBORO, NORTH CAROLINA.

AUTO WHEEL PULLER.

Application filed June 29, 1926. Serial No. 119,387.

The present invention relates to wheel pullers or the like, and aims to provide a novel form of wheel puller which is of the adjustable type, novel means being provided 5 for adapting the device for use in connection with wheels having hubs of various diameters.

Another important object of the invention is to provide a device of this character 10 which may be securely clamped to the hub of a wheel in such a way as to relieve the threads of the hub, to which the pulley is attached, of undue strain, eliminating any possibility of stripping the threads.

15 Another object of the invention is to provide a puller which will exert a direct pull on the wheel under treatment, insuring against the puller twisting to retard the action of the puller.

20 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

30 Referring to the drawing:

Fig. 1 is a longitudinal sectional view through a wheel puller constructed in accordance with the invention and showing 35 the same as applied to a wheel,

Fig. 2 is a sectional view taken on line 2-2 of Fig. 1, and

Fig. 3 is a sectional view taken on line 3-3 of Fig. 1.

40 Referring to the drawing in detail, the device includes a body portion 5 which is hollow, as clearly shown by Fig. 1, the same being of the general outline of a hub cap.

A flange 6 is formed at one end of the 45 body portion and defines a guideway with the shoulder 7, which is formed in spaced relation therewith.

As illustrated by Fig. 2, the base of the 50 body portion is rectangular in formation, one of the sides thereof being cut away to permit of access to the guide way.

The reference character 8 indicates a 55 removable threaded member which is rectangular in formation to fit within the guideway, and as shown, the removable member is

split as at 9, to permit the sides of the removable member to be moved towards each other under the action of the set screw 10 which passes through an opening in the base and has its tapered inner end 11 positioned 60 in a recess formed in the movable member 8.

The opposite end of the body portion is formed with a shoulder 12 adapted to be engaged by the threaded sleeve 13 which is provided with an annular rib 14, the rib 65 being formed with a cut out portion to accommodate the pin 15 so that rotary movement of the sleeve 13 will be prevented when the device is in use.

Operating through the threaded sleeve 13 70 is a pressure bolt 16 which has a reduced inner end portion 17 designed to engage against the outer end of the axle 18 on which the wheel, which in the present showing is indicated at 19, is positioned.

75 In the use of the device, the threaded member which is used in connection with the body portion is positioned within the guideway of the body portion and the device is screwed onto the threaded portion of a wheel hub, when the usual hub cap has been removed therefrom, whereupon the set screw is moved to cause the threaded member to closely engage the threads of the hub and bite into the spaces between the hubs, thereby relieving the threads of undue strain.

80 The pressure bolt is now operated by means of a wrench, until the inner end thereof is forced against the axle 18 with 90 the result that a pulling action takes place.

85 It will be obvious that by removing the threaded member 7 and replacing it with a threaded member having a larger or smaller opening, to suit various requirements, the 95 puller may be used in connection with wheels having hubs of various diameters.

I claim:

1. In a wheel puller, a rectangular body 100 portion having a flange formed at one end thereof, said flange defining a guideway, one edge of the body portion being open to permit access to the body portion, a removable rectangular threaded member split to permit of expansion and contraction thereof, adapted to be slid under the flange, means 105 extending through the body portion and contacting with the rectangular threaded member to cause the rectangular threaded member to clamp the hub of a wheel to be 110

pulled, and means cooperating with the body portion and axle on which the wheel is positioned to pull the wheel from its shaft.

2. In a wheel puller, a body portion, a threaded member removably secured to the body portion and adapted to be positioned on the threaded extremity of a wheel hub, means for clamping the threaded member to the wheel hub, said body portion being hollow, a threaded sleeve in the body portion having a rib, said rib having an opening, a

pin extending through the body portion and into the opening, said pin adapted to hold the sleeve against rotation, and a threaded member operating through the sleeve and adapted to engage the axle on which the wheel is positioned to pull the wheel from the axle.

In testimony that I claim the foregoing as my own, I have hereto affixed my signature.

JOSEPH V. RAY.
